MOBILE SEWING MACHINE

Clifford W. Birch, Jr., 34 Grove St., Lexington, Mass.

Filed Mar. 2, 1959, Ser. No. 54,804

Term of patent 14 years

(Cl. D55—1)

Fig. 1.

Fig. 2.

Fig. 3.

Fig. 4.

Fig. 5.

FIG. 1 is a front elevational view of a mobile sewing machine, showing my new design;

FIG. 2 is a side elevational view;

FIG. 3 is a rear elevational view; and

FIG. 4 is an elevational view showing the side opposite that shown in FIG. 2;

FIG. 5 is a fragmentary perspective view thereof.

The essential features of my design reside in those portions shown in full lines.

I claim:

The ornamental design for a mobile sewing machine, as shown and described.
